UNITED STATES PATENT OFFICE.

HENRY B. CROSS, OF SYRACUSE, NEW YORK.

EQUALIZING DEVICE FOR VEHICLES.

SPECIFICATION forming part of Letters Patent No. 510,676, dated December 12, 1893.

Application filed December 19, 1892. Serial No. 455,625. (No model.)

To all whom it may concern:

Be it known that I, HENRY B. CROSS, a citizen of the United States, residing at Syracuse, in the county of Onondaga and State of New York, have invented certain new and useful Improvements in Equalizing Devices for Vehicles; and I do hereby declare the following to be a full, clear, and exact description of the invention, such as will enable others skilled in the art to which it appertains to make and use the same, reference being had to the accompanying drawings, in which—

Figure 1 is a side or longitudinal elevation of my improved equalizing device for vehicles as operatively applied to a street-car (or other spring vehicle); and Fig. 2 is a like representation of my device as embodying a slight variation or modification in detail construction, and applied substantially similar. Like letters and figures of reference indicate corresponding parts throughout the views of the drawings.

The object of my present invention is to provide an equalizing device for vehicles which, while broadly adaptable by immaterial or slight variations for all varied species of spring-vehicles, is more especially designed for, and particularly calculated for street-cars wherein electricity, traveling cables or horses are utilized as a motive power.

Furthermore, the purpose of my invention is, the production and adaptation of an equalizing appliance for the purposes specified, which, not only is applicable of conjoint attachment to the body and running-gear of street-cars, (preferably those electrically operated,) which are in progress of construction; but equally readily applied to the body and gearing of cars already in active service.

Additionally, the purpose of my invention is, the embodiment of an equalizer device of the nature aforementioned, wherein the equalizing mechanism broadly comprises a compound leverage, stationary fulcrum points, a hinged central connection of the two co-acting levers conjointly forming a compound lever construction, and a loose connection of the non-abutting ends of said levers with the body portion of a vehicle.

Specifically the intent of my invention is, the production of a device of the character described comprising in its detail formation

a novel and co-operative arrangement of its united parts.

My invention consists in the novel features 55 of construction, combination of parts, and operation and co-adaptation hereinafter set forth, and specifically enumerated in the clauses of the claim hereunto annexed.

It is constructed as follows:—1 is the floor- 60 ing-timber or bottom stringers of a car body, 2 (in dotted work) a railway rail or rails, and 3 (also in dotted work) customary car-wheels journaled by bearings in the truck gearing or frame-work of the car's running-gear, and in 65 this instance, by way of exemplification solely, shown as journaled by their axles in the frame-bar 4 of the running-gear frame-work.

Referring directly to my device, A is a 70 compound-lever located a suitable distance beneath the bottom of the car, longitudinally therewith, and preferably located at a point midway the car's width, the lever (suitably connected) extending parallel the car body a 75 satisfactory distance. This compound lever comprises two elongated lever-sections or companion levers B, B, of substantially the comparative length, width and thickness shown, or the proportions and contour varied as de- 80 sired, disposed lineal end to end, their sides perpendicular, and on diametrically opposite planes located normally slightly inclined from a horizontal, which lever sections B, B, are respectively fulcrumed upon the car-wheel 85 axles or between the forward and rearward wheels to the framework of the running-gear, in this instance represented as respectively fulcrumed to vertical standards C, C, by pivot-pins a, a, one disposed transversely central 90 each standard and passing through an opening in the lever-section working in the slot of the standard; which standards are rigidly secured to the frame-bar 4, (or other satisfactory part of the gearing-frame,) by bolts b, b. 95 The companion levers creating in unison the compound-lever A, are respectively fulcrumed centrally or practically centrally their lengths, and, at their inner ends meet centrally between their fulcrum points, forming at such 100 junction a permanent loose-joint or hinged connection D; said central connection of the lever-sections B, B, being indicated in Fig. 1, as a segmental gear connection E, the meet-

ing ends thereat having teeth or cogs *c*, *c*, whose peripheral sweep is described by a semi-circle whose point for describing the arc is located at the pivotal fulcrum center of the 5 respective lever-sections, and thus the meshing of the central toothed ends permits of the raising or depression of the sections while engagingly retained together centrally their fulcrums; while in Fig. 2 the afore-mentioned longitudinally central hinged connection of the compound-lever *A*, entire, is of varied formation, as denoted at *F*, the abutting ends being semi-circular or curved as at 10 *d*, *d*, on similar yet antagonistic curves, described from similarly opposite points, whereby vertically edgewise two convex faces impingingly meet, and said convexed extremities of the lever sections are retained lineally parallel, and yet free to work, by a longitudinally slotted guard or retention plate *G*, provided on a line perpendicularly central with 15 two transverse pivot-pins *e*, *e*, passing through the guard-plate walls and the meeting extremities of the lever-sections lying one 20 against the other in the guard's slotway; a pivot-pin thereby being provided for each of the ends aforesaid, as clearly indicated.

The longitudinally-outward extremity of each lever-section *B*, *B*, (being the forward 25 and rearward terminations of the aggregated compound-lever *A*,) are loosely connected to the flooring-timber or bottom stringers of the car-body either by means of vertical connecting-bars, or links, or rods *H*, *H*, pivotally secured at their lower ends to the contiguous outer extremities of the compound-lever formation *A* by pivot-pins *f*, *f*, and at their upper ends pivotally connected to brackets or hangers *J*, *J*, by pivot-pins *g*, *g*; said brackets 30 being firmly secured to the under side of the car body by bolts *h*, *h*, as shown; or else the outer extremities aforesaid of the compound lever have short longitudinal slots *i*, *i*, respectively, receiving loosely pivot-pins *j*, *j*, 35 extending transversely through the walls of the slotted brackets *J'*, *J'*, and through the slotted opening in the lever's ends, the slots being sufficiently elongated to permit of requisite play thereof on the pins, which attachment in the manner shown is practically analogous to the first illustrated formation, a virtually similar loose or pivotal connection being 40 resultant. Said brackets *J'*, *J'* are firmly secured to under side of vehicle body by suitable bolts *h'*, *h'*.

As is evident, my appliance is susceptible of being erected right within the frame or gearing of the car, as well as located above it. Moreover, that the vertical bars or rods 45 *H*, *H*, may be, if desired, disposed or hung centrally within the customary coiled car-springs.

The construction illustrated in Fig. 1, is the more particularly adapted to be inserted 50 in the frame or gearing of cars being built, or under construction, and that modified form shown in Fig. 2 is especially applicable for

those already built and in use. However, either form of construction may be applied to car-running gear already constructed, although in certain respects, the modified form 55 illustrated in the second figure of the drawings is most applicable.

When my device is erected, within a space 60 allowed for it, in or between the frame-formation of the running gear, it will practically be unobservable to the casual inspector.

The construction shown, both in a broad sense and specifically, insures prevention of the usual oscillation and vibration where- 65 to cars, particularly street-cars, and other vehicles are subject, for the reason that my device properly applied thereto equalizes the customary injurious and disagreeable oscillatory motion of the car or other vehicle, caus- 70 ing as it does, the usual car-springs to operate in unison and with perfect uniformity.

A depression of extremity of the car and contiguous end of the compound-lever necessarily causes the opposite outer end and hinged central portion located midway the 75 points of fulcrum, to assume positions upon a corresponding horizontal plane, *i.e.*, the forward and rearward pivotal extremities of the compound lever and its hinged connected central portion invariably assuming and occupying a plane parallel with the bottom of the car-body. Thus it is evident, that the perfect 80 equalization caused by my equalizer device retains practically continuous the car floor 85 parallel with the gearing frame.

The utilization of my device prevents rock- 90 ing of the running gear or dynamo machinery, pounding of the rails and road-bed, and all other injurious rocking of the car body and 95 its mechanism, and entirely obviating those features of rocking, jarring and acute vibrations so disagreeable and discomforting to passengers in the car.

Obviously, although I illustrate and de- 100 scribe two modified forms of construction of my device, one slightly differing from the other in detail formation, yet not in principle, it is apparent that my device is, so far as detail 105 formation is concerned, susceptible of more or less variations or modifications that would come within the broad purview thereof, and be no departure from the true intent and broad scope of my invention.

Having described my invention, what I 110 claim as new, and desire to secure by Letters Patent, is—

1. In combination with a car and its running gear or truck a system of equalizing levers with their inner abutting ends loosely 115 connected together, at or near their central portions fulcrumed in or on the truck, or gear, their outer extremities loosely connected to the body by adjustable connecting rods or links all combined, thereby insuring the absolute disposal and retention of the levers in a practically horizontal position, parallel with the body and truck, for the purpose set forth and described.

2. A car having equalizing levers B B loosely connected to each other at their inner abutting ends, and at or near their centers fulcrumed in or on the gear or truck, their outer ends connected to the car body by links or connecting rods, thereby insuring normally the retention of the equalizing levers upon a practically horizontal plane, substantially as set forth. 30
- 10 3. In an equalizing device, in combination, equalizing levers B. B. normally located on a practically horizontal plane their inner contacting ends loosely connected together, the levers at or adjacent their centers suitably fulcrumed in or on the running gear or truck, their outer ends connected by links or connecting rods to the body of the car, substantially as specified. 35
- 15 4. In combination with running gear of a car the herein described equalizing device comprising a pair of levers on each side of a car, having their central portions fulcrumed in or on the gear, their inner abutting ends loosely connected together, their outer extremities connected with adjustable connecting rods to the car body, so as to insure in normal operation thereof the disposal of the inner and outer ends of the equalizing levers 40
- 20 on a corresponding horizontal plane parallel to car body substantially as specified. 45
- 25 5. In an equalizing device the equalizing levers B B disposed lengthwise parallel with the car, their inner abutting ends loosely connected together devoid of intermediate connections, said levers at or adjacent their central portions fulcrumed in or on the gear or truck, their outer ends loosely connected by connecting rods or links to the car body, all combined and operating substantially as set forth. 50
6. A car provided with equalizing levers B B fulcrumed midway or thereabout their lengths in or on the running gear or truck, their inner ends loosely connected together in such manner as to insure direct abuttal of the facing ends, and their outer ends loosely connected by links or connecting rods to the car body, all combined and operating as shown and for the purposes described. 55

In testimony whereof I affix my signature, in presence of two witnesses, this 13th day of December, 1892.

HENRY B. CROSS.
